UNITED STATES PATENT OFFICE.

RENE A. MACHON, OF WEST HAZELTON, PENNSYLVANIA.

HEDDLE FOR JACQUARD WEAVING.

Application filed October 28, 1925. Serial No. 65,435.

This invention relates to new and useful improvements in weaving fabrics and particularly to weaving fabrics having designs therein.

5 The principal object of the invention is to weave figured fabrics, with one repeat, regardless of the width of the fabric, or the number of warp ends used, the number of repeats being governed by a single pattern

10 design of the jacquard cards.

Another object is to provide a novel and improved means for controlling the warp threads between the mail eyes, and the lay beam, at closer intervals than the ordinary 15 shed produced by the operation of the warp lifting hooks, whereby to provide binding filler threads for the figure and ground of the fabric.

Another object is to provide a novel and 20 improved mechanism of this character wherein a satin or other weave is accomplished without increasing the number of jacquard hooks, or repeating the design across the jacquard cards.

25 A further object is to provide a weaving method wherein the number of warp threads passed through the mail eyes of the jacquard hooks can be greatly increased, and wherein the individual warp threads are capable of 30 control, independently of the shed motion of the jacquard mechanism, to provide for weaving a single design completely across the fabric, or to weave a figure at any point transversely or longitudinally of the fabric, 35 regardless of the width of the fabric.

Other objects and advantages will be apparent from the following description when taken in connection with the accompanying drawings.

40 In the drawings:

Figure 1 is a vertical sectional view through a portion of a jacquard mechanism, showing the invention, and with the warp threads in lowered position with the exception 45 of certain of the threads which are elevated to provide the binders on the face of the fabric such view being quasi-diagrammatic.

Figure 2 is a similar sectional view, but 50 showing the warp threads lifted by the jacquard hooks, and certain of the threads held down to provide for the binders on the reverse face of the fabric such view being quasi-diagrammatic.

55 Figure 3 is an elevation of one of the heddle frames, operable by the dobby mech-

anism, said frame being adapted to be depressed such view being quasi-diagrammatic.

Figure 4 is a similar view of one of the heddle frames which is adapted to be elevated such view being quasi-diagrammatic.

Figure 5 is a diagrammatic view showing the manner of threading the warp threads from two of the mail eyes, through certain of the heddles of the heddle frames.

Figure 6 is an enlarged detail view of one of the heddles, showing the arrangement of the slot thereof, when used in an elevating heddle frame.

Figure 7 is a similar view of a heddle 70 used in a depressing heddle frame.

Figure 8 is a detail sectional view showing the manner of securing the heddles in the heddle frames.

Referring particularly to the accompanying drawings, 10 represents the warp threads which pass through the mail eyes 11, of the harness strings 12, such strings having the regular lings 13 connected to their lower ends, and the hooks 14, on their upper ends 80 operable by the griffes 15, all of which form parts of the conventional jacquard mechanism, in connection with which the present invention is adapted for use.

In the ordinary operation of devices of 85 this class, the proper number of hooks and heddle strings are provided, and a corresponding number of warp threads passed through their mail eyes, but to provide for the proper number of ends, to produce the 90 quality of fabric desired, the number of repeats must be increased. With the present device this increase of the repeats is obviated, and the warp threads lifted or depressed, for the desired number of sheds, 95 independently of the regular sheds of the hooks, at points between the mail eyes and the lay beam of the loom. Thus a number of sheds, between the mail eyes and the lay beam can be accomplished during one or 100 two of the sheds by the hooks, with the result that a single pattern or design can be woven across a greater width of fabric than heretofore. This is accomplished in the manner, and by the means of the mechanism to be next described.

Disposed between the lay beam 16 and the harness strings 12, are a series of vertically movable heddle frames 17, and carried by each of the frames, and extending vertically 110 therein, are the heddles 18, each having a longitudinal slot 19 formed therein, and ex-

tending from a point adjacent one end of the heddle, to a point adjacent the longitudinal center of the heddle. For purpose of illustration, these heddle frames are divided into 5 two groups of five frames each, the heddles of one group have their slots extending from a point adjacent the upper end, and terminating at a point approximately midway of the length of the heddle, while the slots 10 of the other group extend from points adjacent the lower ends to points a short distance above the longitudinal centers of the heddles, and therefore above the lower ends of the slots of the heddles of the first group. 15 By this arrangement of the slots, it will be seen that, when the jacquard hooks lift the warp threads, during the regular pattern shed, such threads easily move through the slots of certain others of the heddles, without interference. Furthermore, when one of 20 the heddle frames is elevated, from one group, and one is depressed from another group, there will be no binding or interference with the other warp threads, when 25 the hooks perform their regular shedding motion. This is especially seen in Figs. 1 and 2, when the first frame of the elevating group is raised, the second frame of the depressing group will be depressed. The 30 heddles are provided with the eyes 20 through which are disposed the metal strips 21, shown in Fig. 8, such strips being held in the hooks 22, of the upper and lower rails of the heddle frames. As Figures 1 to 5, 35 inclusive, are quasi-diagrammatic, these details cannot be shown. By this construction the binders for the design and ground can be worked separately from the chain of jacquard cards.

40 The heddle frames 17 are each provided with springs 22, yieldably holding the same in normal position, so that one group of frames is held in elevated position, while the other group is held in depressed position. 45 Operating cords 23 are connected to the sides of the frames 17, opposite to that to which the springs are connected, for moving the frames against the tension of the springs, the springs returning the heddle frames to 50 normal position when the pulling action ceases. These operating cords are actuated by the usual dobby mechanism, a portion of which is shown at 24, in Figures 3 and 4, of the drawings.

55 To distinguish the elevating and depressing heddle frames, those which are adapted to be elevated are designated by the numeral 17, while those which are described as moving downward are designated by the numeral 17', the latter being slightly greater in height than the former, although this is not necessarily the case.

For purpose of illustration there are ten warp threads passed through the mail eye 60 of each hook 14, and the ten ends therefrom

passed through the slots of the heddles in the following manner: The first end is passed through the first heddle of the first frame 17 and thence through the first heddle of the first frame 17'. The second warp 70 end is passed through the first heddle of the second frame 17, and thence through the first heddle of the second frame 17'. The third end is passed through the first heddle of the third frame 17 and thence through the first heddle of the third frame 17'. This is proceeded with until the sixth end is reached, said sixth end being passed through the second heddle of the first frame 17, and the second heddle of the first frame 17'. 80 This method is continued until all of the ends from all of the hooks have been passed through slots in the heddles of the heddle frames 17 and 17'. By this construction, and in accordance with the illustration given, the number of hooks used is the same as is ordinarily used, but the number of warp threads is increased ten times, thus permitting a finer quality of fabric to be woven, and also permitting individual manipulation of these warp ends whereby to dispose binder threads on each face of the fabric, at the places desired. This is especially useful in weaving patterns on fabrics, and in producing satin weaves. 85

Thus the machine provides a succession of main sheds of the warp threads in groups of ten, or more, and a succession of secondary sheds of the individual warp ends, after leaving the mail eyes. 100

It is to be understood that by running more or less threads through the mail eyes 11, the quality of the fabric can be changed. Furthermore, by increasing or decreasing the number of heddle frames, in the sets of frames, and entering the threads from the mail eyes through the heddles of said frames, and raising and depressing same, at the proper intervals, different kinds of twills can be produced. 105

The particular arrangement of the slots of the heddles permits the regular shed of the hooks 14, without disturbing the heddles of the frames, and whereby when certain of the heddle frames 17 are raised to produce the binders on one face of the fabric, other heddle frames 17' may be depressed in position to produce the binder threads on the other face of the fabric, as is obvious. As each frame 17 or 17' is moved, it carries with it every fifth thread of the entire number of warp thread ends, which come from the mail eyes. 115

What is claimed is:

The combination with a jacquard mechanism with its string carrying mail eyes, and a dobby mechanism, of a group of threads disposed through each of the mail eyes, and means between the said mechanisms and receiving the individual thread ends from the 120 125 130

said groups, said means being operable by said dobby mechanism for raising and lowering certain of said individual thread ends to produce binders on the opposite faces of 5 the fabric, said means including individually operable frames, heddles in said frames, the heddles of certain of the frames having slots extending from points adjacent one

end and terminating intermediate the ends thereof, while the slots of the other heddles extend from points adjacent the other ends of the heddles and terminate beyond the longitudinal centers thereof 10

In testimony whereof, I affix my signature.

RENE A. MACHON.
